US00D974181S

(12) **United States Design Patent** (10) Patent No.: **US D974,181 S**
(45) Date of Patent: ** Jan. 3, 2023

(54) **BOTTLE**

(71) Applicant: **Medline Industries, LP**, Northfield, IL (US)

(72) Inventors: **Alyson Ovitt**, Gurnee, IL (US); **Kimberly Washington**, Chicago, IL (US); **Mark Krukonis**, Libertyville, IL (US); **Juniwati Katopo**, Elgin, IL (US)

(73) Assignee: **Medline Industries, LP**, Northfield, IL (US)

(**) Term: **15 Years**

(21) Appl. No.: **29/712,471**

(22) Filed: **Nov. 8, 2019**

(51) LOC (14) Cl. **09-01**

(52) U.S. Cl.

USPC **D9/682**; D9/690; D9/691

(57) **CLAIM**

The ornamental design for a bottle, as shown and described.

DESCRIPTION

FIG. 1 is a perspective view of a bottle in accordance with our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the figures illustrate portions of the bottle that form no part of the claimed design.

1 Claim, 6 Drawing Sheets
